(57) **CLAIM**

The ornamental design for an asphalt paver, as shown and described.

DESCRIPTION

FIG. 1 is a right front perspective view of an asphalt paver showing our new design.

FIG. 2 is a right side view thereof.

FIG. 3 is a front view thereof

FIG. 4 is a rear view thereof; and,

FIG. 5 is a top plan view thereof.

The broken line showing of an asphalt paver is included for the purpose of illustrating environmental structure and forms no part of the claimed design.

1 Claim, 5 Drawing Sheets

FIG. 1

FIG. 3

FIG. 4

FIG. 5
